INCLINED GUIDE FOR SLICING MACHINE
CHUTES

Arnold W. Lundell, East Portchester, Conn., assignor to Globe Slicing Machine Co., Inc., Stamford, Conn., a corporation of New York

Application January 21, 1949, Serial No. 72,038

3 Claims. (Cl. 146—102)

1

This invention relates to guides for holding items to be cut by a slicing machine at an angle to enable, when slicing flat strips of meat, bacon, Bologna and the like, obtaining a slice wider than the thickness of the item being sliced.

Among the objects of the present invention, it is aimed to provide an improved guide operatively connected to a slicing machine chute, which guide may with facility be folded up out of the way when conventional use of the chute is desired, and which in turn may with facility be moved into use to guide a flat strip of meat, Bologna or the like, while the same is supported by this chute.

These and other features, capabilities and advantages of the invention will appear from the subjoined detail description of one specific embodiment thereof illustrated in the accompanying drawings, in which.

Fig. 1 is a perspective of a slicing machine partly broken away equipped with the present improved guide.

Fig. 2 is a perspective of the chute detached from the slicing machine showing the guide in full lines folded out of the way and in dash and dot lines moved into position for use.

Fig. 3 is a plan view of the chute looking vertically at one wing.

Fig. 4 is an end view of the chute shown in Fig. 3.

Fig. 5 is a fragmental end view on the line 5—5 of Fig. 4.

In the embodiment shown there is illustrated a conventional slicing machine 1 having a rotatable knife 2 in alignment with the table 3 which is adjustable relative to the knife 2 according to the thickness of slice to be cut, the plane of the knife 2 and table 3 as shown in Fig. 1 being preferably disposed at an oblique angle to the vertical so that the meat may rest not only on the table 3, but also on one or both wings 4 and 5 of the chute 6. The wings 4 and 5 form a dihedral angle with one another and may be disposed at right angles to one another as shown in Fig. 3 to form a dihedral angle with their connecting or dissecting edge 7 disposed at an oblique angle to the vertical and substantially vertical to the plane of the table 3. Similarly the wings 4 and 5 may be disposed substantially vertical to the plane of the table 3 but so inclined to the vertical that a food product or the like when positioned between the wings 4 and 5 may rest on one or both, and under the force of gravity slide along the wings 4 and 5 into engagement with the table 3.

2

In the present instance the wing 4 has a rectangular opening 8 formed adjacent the edge 7 and in alignment with the rectangular depression or recess 9 continuing down to the lower edge 10 of the wing 4 adjacent the table 3.

In alignment with the edge 10 at the lower edge of the recess 9, there is hingedly connected the plate guide 11. This guide 11 is conformed to extend from the edge 10 of the wing 4 to the outer edge 12 of the wing 4 and the full width of the recess 9 and adjacent opening 8, see particularly Fig. 2.

For anchoring the guide 11 in both its innermost, out-of-the-way position, that shown in full lines in Fig. 2, and also in its outermost guiding position, there is provided the items now to be described. In the first place the wing 5, composed as an instance of aluminum or other light weight material, may have an arcuate wearing strip 13 formed thereon, which wearing strip 13 may be composed of any suitable hardened metal to resist undue wear. At the inner end of the strip 13 on the wing 5 there is formed the recess or depression 14. At the outer end of the strip 13 and in the extension 15 extending from the wing 5 at the edge 7, there is provided a similar recess or depression 16. These depressions 14 and 16 are provided in the present instance, see Fig. 5, to receive the projection or plunger 17 at the lower end of the finger 18 formed on the lever 19 pivotally connected to the guide 11 by the screw 20. The lever 19 has its outer free end 21 extend slightly beyond the enlargement 22 at the upper end of the guide 11, see Figs. 2 and 5. The lever 19 has an upwardly extending finger 23 extending into the recess formed in the boss 24 to engage the spring 25 which urges the lever 19 downwardly so that its projection 17 may be spring-pressed either into engagement with the depression 16, or into engagement with the wearing strip 13 or the depression 14.

In the operation of the aforesaid, when the chute 6 is used in the conventional way without the guide 11, the guide 11 is positioned in the depression 9, the full line position shown in Fig. 1, where the projection 17 rests in the recess or depression 16 in the extension 15, being urged into engagement with such depression 16 by the spring 25 acting on the lever 19. When it is desired to slice a flat strip of meat, such as bacon, Bologna or the like, with a wider slice than the width of the strip of bacon, or Bologna, then the guide 11 is swung into the full line position shown in Fig. 3. The operator in such case is guided by the

projection portion 21 to engage the lower edge of the lever 19, Fig. 5, and raise it so that the projection 17 clears the depression 16 and is in position to ride on the wearing strip 13 when the operator presses the guide 11 away from the wing 4 into the position shown in Fig. 3 when the projection 17 will need the urgency of the spring 25 to drop into the depression 14. Thereupon the item 26 to be sliced, see the dash and dot line of the item 26 in Fig. 3, is placed on the wing 4, against the outer face of the guide 11 and the slicing machine is ready to be operated in the usual way by the operator engaging the handle 27 and reciprocating the chute 6 to and fro relative to the knife 2. In the operation of this machine the operator may find it expedient to engage the handle 27 with his right hand and engage the item to be sliced with his left hand into firm engagement with the guide strip 11 while the chute 6 is being reciprocated to and from the knife 2.

It is obvious that various changes and modifications may be made to the details of construction without departing from the general spirit of the invention as set forth in the appended claims.

I claim:

1. A guiding device for a slicing machine chute wherein the slideable chute has a first wing and a second wing forming a dihedral angle with one another and at an oblique angle to the vertical with the dihedral angle between the wings at the lower edges of the wings, and wherein a rotatable knife and a platform, the planes of which are substantially parallel to one another, are also disposed at an oblique angle to the vertical but substantially adjacent to and vertical to the two wings, characterized by a plate pivotally connected to the lower free edge of said first wing disposed adjacent to the plane of the knife and substantially vertical to said second wing, said first wing being the advance wing during slicing operation and having a recess conforming in depth, width and length to the dimensions of said plate guide to receive the same with the exposed face of the plate guide flush with the exposed face of the first wing, said plate guide being movable across said second wing, and means for anchoring said plate guide either flush with said first wing or to form a dihedral angle with said first wing in guiding position.

2. A guiding device of the character set forth in claim 1 in which the anchoring means includes depressions formed in said second wing, a spring-pressed plunger operatively connected to said plate guide, an arcuate wearing strip composed of a hardened metal extending from one depression to the other to receive said plunger and enable the same to slide along said wearing strip when moving from one depression to the other with the plate guide being disposed vertical to said second wing but spaced therefrom and clearing the same when swinging across the same, relying entirely upon the sliding contact of said plunger on said wearing strip to slidably support the same.

3. A guiding device of the character set forth in claim 1 in which the anchoring means includes depressions formed in said second wing, a lever pivotally connected to said plate guide, a plunger on said lever, a spring operatively connected with said lever to urge said plunger into said depressions, in turn to anchor said plate guide in predetermined positions, the free end of said lever extending beyond the free end of said plate guide to facilitate manipulation thereof, and an arcuate wearing strip composed of a hardened metal extending from one depression to the other to receive said plunger, with the plate guide being disposed vertical to said second wing but spaced therefrom and clearing the same when swinging across the same, relying entirely upon the sliding contact of said plunger on said wearing strip to slidably support the same.
